DATA INSCRIBER OR THE LIKE

Seton Cottier and John J. Natoli, Woodstock, N.Y., assignors to International Business Machines Corporation, Armonk, N.Y., a corporation of New York

Filed Dec. 22, 1967, Ser. No. 9,882

Term of patent 14 years

U.S. Cl. D26—5
Int. Cl. D14—02

FIG. 1

FIG. 2

Des. 213,562

PAGE 3

FIG. 3

FIG. 4

FIG. 1 is a front, left and top perspective view of a data inscriber or the like showing our design.

FIG. 2 is a front elevation view thereof.

FIG. 3 is a right side elevation view thereof.

FIG. 4 is a rear elevation view thereof.

It is to be understood that the keyboard is continuous throughout the area indicated by broken lines in FIGS. 1 and 2.

We claim:

The ornamental design for a data inscriber or the like, substantially as shown and described.
